**TOP AND SEPARABLE HOLDING MEANS
 THEREFOR**
 Everett J. Blyheid, 40 Ralph Ave., Brooklyn, N.Y.
 Filed Mar. 13, 1964, Ser. No. 351,778
 1 Claim. (Cl. 46—72)

This invention relates to toys, and more particularly to spinning tops.

A primary object of the present invention is the provision of a spinning top of novel conformation, a string, and in combination therewith an accessory in the form of a relatively rigid bar rectangular in cross-section. This combination when used as set forth below or in any equivalent manner, will enable the user to spin the top or spinner at a very high rate of rotation and with such power that it will continue to spin for a long time when compared with an ordinary spinning top.

Another object of the invention is the provision, in combination with a spinning toy and a string adapted to be wound thereon, of a stick of relatively rigid material having two opposed relatively wide sides and two opposed relatively narrow sides, with a hole extending through the stick near one end thereof between the said wide sides thereof.

The above as well as additional objects will become apparent in the following description wherein reference numerals refer to like-numbered parts in the accompanying drawing. It is to be noted that the drawing is intended primarily for the purpose of illustration and that it is therefore neither desired nor intended to limit the invention necessarily to any or all of the exact details shown or described except insofar as they may be deemed essential to the invention.

Referring briefly to the drawing,

FIG. 1 is a side elevational view of the combination device, in position to be discharged to cause the spinner toy to spin.

FIG. 2 is a sectional view taken on the line 2—2 of FIG. 1.

FIG. 3 is a side elevational view of the accessory stick per se.

FIG. 4 is a side elevational view, showing the reverse of the side shown in FIG. 1.

Referring in detail to the drawing, the numeral 10 indicates a spinning toy which, although in principle similar to a common spinning top, has a different conformation. As illustrated, the spinner consists of a globular head 11 and an elongated cylindrical axial stem 12 extending from the head 11. A length of cord or string 13 is provided, and in addition thereto an accessory in the form of a stick 14 completes the combination.

The stick 14 is of rectangular cross-section, and is defined by the two opposed wider sides 15 and 16 and the two opposed narrower sides or edges 17 and 18. Near one end of the stick a circular hole 19 extends therethrough at right angles to the sides 15 and 16.

The preferred manner of setting up the device for use is to pass the string through the hole 19 from the side 15 to the side 16, and winding the portion extending from the side 16 into one or more coils 20, of which but one is shown, about the stem 12. This may be done with the

2

right hand while firmly holding the stick and string with the left hand. Upon completion of winding the string about the stem, the end of the string protruding through the side 16 is wound upon one or more fingers of the right hand, the stem meanwhile being held in the left hand and urged against the stick, in the relative positions shown in the drawing. The thumb of the right hand is then placed firmly on the top of the globe 11. Then, in a bending position about a foot above the floor, and being careful to position the combination so that the stem 12 is perpendicular to the floor, the string is pulled hard by the right hand through the hole 19, and at the same instant the thumb is released from the globe 11. This will cause the spinner to drop to the floor while rotating at a very high speed, and upon meeting the floor the spinner will continue to rotate for a relatively long time. The use of the accessory stick 14, in substantially the manner indicated in the drawing, is the source of great augmentation of the rotational force applied to the spinner.

20 The spinner 10 including the globular head 11 and the stem 12 may be made of any suitable or desired material and they may be finished in any color or combination of colors.

25 The coils 21 shown in FIG. 4 represent coils of the portion of the string protruding from the side 16 of the stick, which are, in use, wound upon one or more fingers of the right hand.

30 The invention having thus been described, what is claimed and desired to be secured by Letters Patent, is as follows:

35 In combination, a spinner including a substantially globular head and an elongated cylindrical stem extending axially from the head, a length of string, a stick rectangular in cross-section having two opposed relatively wide sides and two opposed relatively narrow sides, the stick having a hole near one end thereof extending through said wide sides thereof, the string being adapted to be passed through said hole thus positioning one end of the string on one wide side of the stick and the other end 40 thereof on the opposite wide side thereof, the portion of the string extending from said one wide side thereof being adapted to be wound about said stem and the wound stem being positioned adjacent said hole and held in said position by one hand of the operator, the remainder of the string extending from the other wide side of the stick being adapted to be wound upon at least one finger of the other hand of the operator and with the thumb of said other hand pressed upon the top of said head, the spinner being adapted to be discharged upon the floor in upright position by simultaneously pulling said remainder of the string and removing the thumb from said head while firmly holding the stick in said one hand.
